METHOD AND APPARATUS FOR TREATMENT
OF GASEOUS HYDROCARBON MIXTURESPaul V. Mullins, Amarillo, Tex., assignor to the
United States of America as represented by the
Secretary of the Interior

Application December 31, 1948, Serial No. 68,445

7 Claims. (Cl. 62—122)

(Granted under the act of March 3, 1883, as
amended April 30, 1928; 370 O. G. 757)

1

The invention herein described and claimed may be manufactured and used by or for the Government of the United States of America for governmental purposes without the payment of any royalties thereon or therefor.

This invention relates to improvements in the art of separating mixed gases by liquefaction and rectification, being particularly useful in the separation of the constituents of natural gas, whereby at least one of the constituents of the natural gas is separated and the remaining gaseous mixture is enriched in the other constituents, thereby enhancing the value of the gas.

It is an object of the invention to provide a practical and efficient method and apparatus for the separation, removal and recovery of diluent nitrogen from certain natural gas compositions of high nitrogen content by liquefaction and fractionation.

It is a further object of the invention to treat gaseous mixtures composed essentially of methane and nitrogen by compression and expansion of the mixture, combined with utilization of the refrigerative capacity of the several fractions separated in the operation as to effect substantial separation of the nitrogen and the methane, after a preliminary separation of the heavier hydrocarbons, propane, butane and pentane (with some ethane) and helium, if desired.

It is a further object of my invention to effect a substantially complete removal of nitrogen from such natural gas compositions by passing compressed natural gas of high nitrogen content in counter-current indirect heat exchange with cold effluent nitrogen and methane, in a plurality of separate zones, with intermediate separation and withdrawal of the heavier hydrocarbon gases, propane, butane and pentane, liquefying the resulting cooled and stripped gas by adiabatic expansion thereof, rectifying the cold liquid mixture of nitrogen and methane to separate the nitrogen as an overhead vapor fraction while maintaining the substantially nitrogen-free methane as a liquid fraction and utilizing the refrigerative capacity of these fractions to cool compressed natural gas feed to the process.

These and other objects will be apparent from the following description of my invention.

The method is particularly applicable to natural gas and similar mixtures of gases containing low molecular weight hydrocarbons and appreciable amounts of nitrogen as a diluent. In some natural gas fields the nitrogen content is so high that exploitation thereof has been seri-

2

ously retarded or prevented altogether. By removal of the nitrogen from the natural gas and/or similar gaseous mixtures, the concentration of the remaining components is increased, thereby raising the fuel value, lowering the viscosity and specific gravity, and other improvements in the physical properties.

Separation of nitrogen from gaseous mixtures of the type mentioned will provide the following benefits:

1. Increase the heating value, with consequent increased marketability, of the gas from certain fields.
2. Make available for use as a chemical raw material, natural gas from certain fields not now utilized because of the high nitrogen content.
3. Increase the effective capacity of long distance pipe lines by eliminating, in the field, the nitrogen content of the gas now being transported through these lines.
4. Increase the efficiency of pipe line transportation through improvement of the flow characteristics of the natural gas supply.

Broadly such a process is carried out by passing the gaseous mixture counter-current to cold separated constituents in order to bring about liquefaction of the major constituents, and separation of practically pure nitrogen followed by evaporation of the residual liquid and recovery of the gases, with an enhanced value, by counter-current heat exchange with relatively warm gas feed to the process. If helium is present in the natural gas, it may also be recovered before separation of nitrogen and methane.

In the attached drawing the single figure shows more or less diagrammatically a suitable system for applying the invention to the separation of nitrogen (and helium) from natural gas. A, AA and B are heat interchangers in which the entering compressed gaseous mixture is cooled counter-currently by returning enriched gas and separated nitrogen. In interchanger C the gases may be further cooled and partly liquefied by heat exchange with an auxiliary refrigerant supplied by the unit L.

In separator D heavier (molecular weight above ethane) hydrocarbons, which have liquefied are removed from the cooled gaseous mixture.

In interchanger E the stripped gaseous mixture is further cooled by counter-current heat exchange with enriched gas. The chilled mixture is expanded through throttling valve 6 in line 14, into separator F for a preliminary separation of gaseous helium and nitrogen from the liquefied

methane. From separator F the resulting vapor and liquid products pass into heat exchanger G, and are further cooled by separated nitrogen from fractionator H. Heat exchanger G serves as a fractional condenser so that the major portion of the nitrogen in the vapor fraction is condensed with the liquefied methane. Effluent gaseous nitrogen from condenser G is expanded in engine M, and then is passed through exchanger AA, before leaving the system, as practically pure nitrogen. Engine M may be used to drive refrigerating unit L for compressing the auxiliary refrigerant which is passed through interchanger C.

The mixture of liquefied nitrogen and methane is passed to fractionator H for separation of the nitrogen as overhead vapors and methane in liquid form. Pump K removes liquid mixture accumulating in the lower portion of fractionator or rectifier H and returns it to interchanger E for cooling the incoming gas, whence it passes through interchanger B to yield the desired enhanced mixture of hydrocarbon gases.

The conditions of operation on a high nitrogen content natural gas feed are as follows:

The raw gas feed compressed to 300-600 p. s. i., depending upon gas composition and conditions of operation, and suitably treated to remove water vapor and all acidic gases such as CO₂ and H₂S enters at 1. If no H₂S is present in the raw gas feed, the CO₂ and water vapor may be removed by having a duplicate set of interchangers A, AA and B, which would permit intermittent use of first one set and then the other of the interchangers as so-called cold accumulators to remove CO₂ and water and to be alternately warmed and thawed by passage therethrough of raw gas feed. However, the arrangement shown and specified is preferred. The incoming raw gas feed stream is divided at 2 and again at 2A and passed through interchangers A, AA and B, where the divided streams are cooled by interchange of heat to cold outgoing products and then rejoin at 4 and 4A to again form a single stream. The major portion of the incoming raw gas feed would normally pass through interchanger B and only those quantities necessary to interchange heat with the smaller fractions of outgoing separated products pass through exchangers A and AA. The amounts of raw gas feed passing through each of the interchangers A and AA (and B) are controlled by valves 3 and 3A respectively, which can be of an automatic thermal type eliminating the necessity for manual manipulation.

The partly-liquefied raw gas feed enters interchanger C, where it is further cooled and liquefied by interchange of heat to a cold circulating refrigerant supplied by the auxiliary refrigerator unit L. The two-phase mixture then enters separator D, where the gas and liquid phases are separated and the latter is withdrawn for utilization or further processing elsewhere. This fraction constitutes the more readily liquefiable or heavier hydrocarbon fraction which in a natural gas is composed of propane, butane and heavier hydrocarbons, with perhaps a small fraction of ethane. However, a larger amount or fraction may be withdrawn, if convenient and practical, and thus reduce correspondingly the amount of liquids that must be handled in separator G and fractionator H. Any portion of these hydrocarbons which it is desired to return to the cycle and which possess some recoverable refrigeration can be injected into the return processed gas stream at some appropriate point of low pressure, such as the upstream return side of interchanger

A. The interchanger surfaces provided in interchangers B, C and E are selected to establish and maintain predetermined temperature and phase equilibrium conditions for withdrawal of the desired (heavy) hydrocarbon fraction from separator D. The process cycle may be made to operate satisfactorily without auxiliary refrigeration unit L or interchanger C by utilizing refrigeration otherwise available as mentioned herein and by so proportioning the heat exchange between interchangers B and E as to provide the desired liquid fraction in separator D. However, the arrangement shown is preferred as a means of supplementing the overall refrigeration requirements of the process and more specifically to provide that needed to permit withdrawal of cold liquid products in quantity from the system at separator D.

The gas phase from separator D passes through interchanger E where it is further cooled and partly liquefied by interchange of heat to cold outgoing products, namely, the gaseous mixture from which nitrogen and other desired constituents have been selectively extracted as described later herein.

The partly liquefied raw gas feed is then expanded by throttling at valve 6 to a somewhat lower pressure, depending upon the composition of the raw gas and the conditions of operation, and passes into separator F where the gas and liquid phases are separated, the former entering the condenser G at a suitable point 7 on the side of the vessel while the latter enters the same vessel at 8 near the bottom. F facilitates disengagement of the gas from the liquid phase, subsequently completed in condenser G. Also, in condenser G, which preferably is of shell and tube construction, the gas and liquid phases are further cooled by interchange of heat to cold outgoing products and the former, consisting principally of helium and nitrogen when processing natural gas, is rectified with some increase in the helium concentration or purity before withdrawal at 9 at the top of separator G. The refrigerative capacity of the cold helium-nitrogen mixture of crude helium, if sufficient in volume may be recovered in any convenient manner if desired. Such heat interchange, as well as any subsequent treatment and/or purification of separated helium forms no part of the present invention.

If little or no helium is present in the raw gas feed, separator F and condenser G may be eliminated from the process cycle. However, condenser G serves as a temperature stabilizing chamber for the cold liquids therein and thus permits greater stability of subsequent fractionation of the liquid and therefore use of condenser G is preferred. While maintaining a liquid seal in the bottom of condenser G, liquid is withdrawn, its flow controlled by valve 10, and passed without substantial pressure reduction to rectifier H at point 11 about midway of the height of the column.

Rectifier H is a conventional packed or bubble plate column in which the liquefied gas mixture is fractionated to separate virtually pure nitrogen as an overhead vapor while withdrawing from the bottom thereof, virtually nitrogen-free hydrocarbon liquid, principally methane when processing natural gas. Heat required for the fractionation is supplied in the base of the fractionator H through coil 12 by a side stream of warmer raw feed gas taken from the cycle at some convenient point such as 13 and returned 75 at a convenient point of lower pressure such as

14 with control of the flow by valve 15. Liquid nitrogen as reflux is added to the top of the column at 24 from a source described later herein, while maintaining a liquid seal in the bottom of fractionator H, liquid is withdrawn by cold liquid pump K which restores a part of the pressure originally on the raw gas feed while passing the cold liquids through interchangers E and B to cool incoming raw gas feed and to discharge at 17 at near atmospheric temperature a processed gas substantially free of nitrogen, helium, and certain heavy hydrocarbon constituents. The cold liquid pump can be omitted and the cold liquid fraction allowed to pass through interchangers E and B at or near the prevailing pressure with resulting warming and regassification and then be recompressed as desired following discharge at 17 at near atmospheric temperature. However the arrangement shown, using the cold liquid pump is preferred as it results in reduced overall power consumption when the processed gas is to be compressed to a higher pressure. Cold nitrogen vapor leaves the top of fractionator H at 18, a portion going to one pass of liquefier J (at 20) without substantial reduction in pressure while the balance passes through interchanger-type separator G where it cools the products therein as previously described and emerges therefrom at 21 warmed somewhat in temperature and is then expanded through a reciprocating engine or turbine M to near atmospheric pressure which results in the performance of work and cooling of the nitrogen which is then utilized as refrigerant to cool a portion of incoming raw gas feed in interchanger AA* followed by discharge at near atmospheric temperature at 22. Expansion unit M is shown as a source of power for auxiliary refrigeration unit L, but, depending upon the condition of operation, might be used to drive cool liquid pump K or reflux pump N. The expansion unit M could be omitted and the outgoing cold nitrogen throttled to near atmospheric pressure after leaving fractionator H and before entering separator G and thus afford a similar arrangement though somewhat less cooling for refrigeration purposes. However, the arrangement shown in Figure I is preferred as providing greater refrigeration and permitting a reduction in power otherwise required for the process.

A part of the hydrocarbon liquids in the bottom of fractionator H is throttled through valve 16 to near atmospheric pressure and is passed through liquefier J where it provides refrigeration to liquefy nitrogen under pressure in the other circuit of the interchanger. The hydrocarbon mixture emerging from the top of the liquefier J is passed to interchanger A to cool a portion of the incoming raw gas feed and is finally discharged at near atmospheric temperature at 25 for use as low pressure fuel gas or to be recompressed and commingled with the main stream of processed gas out at 17. Where the quantity of hydrocarbon liquid utilized in liquefier J is appreciably in excess of the quantity of nitrogen removed in the process, it is preferred to pass hydrocarbon vapor instead of the nitrogen vapor through separator G for rectification of the gas phase and cooling of the liquid phase therein. Or both hydrocarbon and nitrogen vapors may be passed through separator G by provision of separate circuits therethrough. In either case, passage of vapors through G would be followed by passage through interchangers A and AA as indicated and previously described.

Liquid nitrogen is withdrawn from liquefier J at substantially a uniform rate by reflux pump N and discharged into the top of fractionator H at 24 as reflux for the fractionating process. Reflux pump N may be eliminated by placing liquefier J at a higher elevation than the top of fractionator H and utilizing gravity flow of liquid nitrogen reflux from J to H. However, use of reflux pump N permits better control of the quantity of reflux added to H and tends to improve the operating stability thereof. Thus use of the reflux pump is a preferred arrangement.

Typical of the results that may be obtained with natural gas are the data given in the following examples:

Example I.—Gas compositions (gas "A")

	Before removal of nitrogen and heavy hydrocarbons	After removal of nitrogen	After removal of nitrogen and heavy hydrocarbons
20			
Nitrogen.....	9.7		
Methane.....	79.4	87.9	93.1
Ethane.....	5.9	6.5	6.9
25			
Propane.....	3.3	3.7	
Butane, plus.....	1.7	1.9	

Example II.—Gas compositions (gas "B")

	Before removal of nitrogen and heavy hydrocarbons	After removal of nitrogen	After removal of nitrogen and heavy hydrocarbons
30			
Nitrogen.....	27.3		
Methane.....	65.9	90.6	94.7
Ethane.....	3.7	5.1	5.3
35			
Propane.....	1.8	2.5	
Butane, plus.....	1.3	1.8	

Example III.—Gas compositions (gas "C")

	Before removal of nitrogen and heavy hydrocarbons	After removal of nitrogen	After removal of nitrogen and heavy hydrocarbons
40			
Nitrogen.....	15.0	0	0
45			
Methane.....	73.0	85.9	92.4
Ethane.....	6.0	7.0	7.6
Propane.....	4.0	4.7	0
Butane, plus.....	2.0	2.4	0

By calculation it can be shown that in Example III the original heating value of the gas (1018 B. t. u./cu. ft.) was raised 17.7 percent (up to 1198 B. t. u./cu. ft.) after the nitrogen removal, and 5.3 percent (up to 1072 B. t. u./cu. ft.) after nitrogen and heavy hydrocarbon removal.

The results indicate that to improve the heating value alone, it is preferable to leave the heavy hydrocarbons in the gas. However, removal of them so improves the handling properties of the resulting gas, in pipe lines, etc., that in our preferred process, they are always removed, prior to separation of the remaining gases from the nitrogen.

While any appreciable amount of helium can be recovered, if this is of economic importance, the actual recovery of the small helium content (0.2 to 2.0% by volume) in some natural gas is not an essential part of this invention.

As used herein and in the appended claims, the term methane is not limited to substantially pure methane alone, but also to include methane-ethane mixtures in the proportions customarily found in natural gas compositions.

While I have, in accordance with the patent laws, described and shown my invention in a pre-

ferred form, it should be understood that the process and apparatus are not limited to the specific description herein, but is capable of various modifications without departing from the spirit of the invention, and that all such modifications as fall within the scope of the appended claims are intended to be included therein.

I claim:

1. A process for the treatment of gaseous hydrocarbon mixtures containing a substantial proportion of nitrogen as a diluent comprising refrigerating a stream of the gas under superatmospheric pressure with effluent methane in a first heat exchange zone, liquefying the nitrogen and methane of the gas by adiabatic expansion thereof followed by heat exchange with colder nitrogen vapors in a second heat exchange zone, refluxing the resulting vapor and liquid fractions with liquid nitrogen in a rectifying zone to separate the nitrogen as a vapor fraction and the methane as a liquid fraction, vaporizing a portion of the liquid fraction in heat exchange with a portion of the nitrogen vapors, thereby producing liquid nitrogen for reflux in the rectifying zone, and utilizing the remaining vapor and liquid fractions for cooling the gas being treated in said second and first heat exchange zones.

2. A process according to claim 1 in which additional refrigeration is supplied to the process by expansion of the nitrogen from the second heat exchange zone.

3. Apparatus for the separation of gaseous mixtures by liquefaction and rectification comprising, in combination, a first heat exchanger, means for supplying a gaseous mixture under pressure to said first heat exchanger, a second heat exchanger in series with said first heat exchanger, means for withdrawing the relatively cold fluid mixture from said second heat exchanger, throttling means for controlledly reducing the pressure of said fluid mixture as it is withdrawn from said second heat exchanger, a condenser including a cooling coil for receiving said fluid mixture under reduced pressure, a rectifier, means for transferring to said rectifier liquid accumulating in said condenser, means in said rectifier for withdrawing a vaporous overhead fraction, means in said rectifier for withdrawing a liquefied bottom fraction, means for supplying vapors from said rectifier to the cooling coil of said condenser, means for supplying at least a portion of the liquefied bottom fraction from said rectifier to said second heat exchanger, means on said first heat exchanger for withdrawing the thereby warmed and vaporized bottom fraction, and means connected with the outlet of the cooling coil of said condenser for withdrawing the effluent overhead fraction.

4. A process for the treatment of natural gas of high nitrogen content comprising precooling

the natural gas under superatmospheric pressure in a first heat exchange zone with cold methane gas derived from the process to a temperature at which hydrocarbons heavier than ethane are condensed, separating the resulting liquid hydrocarbon fraction, passing the stripped natural gas in indirect heat exchange with effluent liquid methane in a second heat exchange zone thereby vaporizing the liquid methane and further cooling the stripped and cooled natural gas, then passing the resulting vapors through a third heat exchange zone in indirect heat exchange with colder effluent nitrogen vapors, rectifying the resulting liquid and vapor fractions with liquid nitrogen, thereby separating the methane as a liquid fraction and the nitrogen as an overhead vapor fraction, and utilizing at least a portion of these fractions as the coolant in the said second and third heat exchange zones, respectively.

5. A process as in claim 4 in which a portion of the liquid methane fraction is vaporized under reduced pressure in indirect heat exchange with a portion of the nitrogen vapors, thereby producing the liquid nitrogen for rectifying the liquid and vapor fractions from the third heat exchange zone.

6. A process for the improvement of a hydrocarbon gas of high nitrogen content which comprises cooling said gas under superatmospheric pressure by indirect heat exchange in at least one heat exchange zone with vaporizing liquid methane derived from the process, further cooling said gas by adiabatic expansion thereof, rectifying the resulting liquid and vapor fractions with a liquid nitrogen reflux, thereby separating methane as a liquid fraction and nitrogen as an overhead vapor fraction, utilizing the liquified methane to cool incoming warm gas by vaporization thereof in indirect heat exchange with said warm gas, and utilizing the refrigerative capacity of a portion of said liquid methane for cooling a portion of said nitrogen vapors, thereby producing liquid nitrogen for reflux in said rectifying zone.

7. A process according to claim 6 in which the gas fed to said process is under a pressure of from 300 to 600 lbs./sq. in.
